UNITED STATES PATENT OFFICE.

CHARLES J. ANDERSON AND WILLIAM H. VAN DYKE, OF CORNING, NEW YORK.

COMBINATION LOCK.

1,423,384.

Specification of Letters Patent.

Patented July 18, 1922.

Application filed October 20, 1921. Serial No. 509,116.

To all whom it may concern:

Be it known that we, CHARLES J. ANDERSON and WILLIAM H. VAN DYKE, citizens of the United States, residing at Corning, in the 5 county of Steuben and State of New York, have invented certain new and useful Improvements in Combination Locks, of which the following is a specification.

This invention relates to locks for the combination class, and has for one of its objects 10 to provide a simply constructed device of this character of improved construction and increased efficiency.

Another object of the invention is to provide 15 a device of this character of increased simplicity and more particularly for application to freight cars or car doors to protect the contents from access by unauthorized persons.

With these and other objects in view the invention consists in certain novel features of construction as hereinafter shown and described and then specifically pointed out in the claims, and in the drawings illustrative 25 of the preferred embodiment of the invention:—

Figure 1 is a side elevation of a portion of a door and its jamb with the improved lock applied.

Figure 2 is an enlarged sectional detail.

Figure 3 is an enlarged sectional elevation.

Figure 4 is an enlarged sectional detail.

Figure 5 is a detail of the swinging rack 35 bars.

Figure 6 is a detached perspective view of the sliding bolt.

The improved device may be readily adapted for use in securely locking a movable structure or member to a stationary 40 member, or to lock two movable members together, but is more particularly adapted for securing a sliding car door to its jamb or casing, and for the purpose of illustration is shown thus applied, a portion of the door being indicated at 10 and the jamb at 11.

Attached to the jamb 11 is a casing or housing 12 having an internal transverse 45 stop 13, and attached to the door 10 is another and larger casing 14.

Pivoted at 15 within the casing 14 is a lock lever 16 adapted to enter the casing 12

and having a hook 17 at one end to engage over the stop 13, as shown in Figure 3. 55

The inner part of the lever 16 engages in a recess in the back wall of the casing 14, and is yieldably held in stop engaging position by a spring 18.

A bolt 19 is slidably disposed in a guide-way 20 in the rear wall of the casing 14 and held in position by a keeper plate 21. The bolt 19 is formed with a notch 22 in one edge and a longitudinally directed gear rack 23 in the other edge as shown more 60 particularly in Figure 6.

A short shaft 24 is mounted for rotation in the casing 14 and carries a gear wheel 25 engaging the rack 23 and is also provided with an arm 26 depending from the inner 70 end.

Extending through the casing 14 is a rock shaft 27 having an external operating arm 28 adapted to actuate the shaft and another arm 29 within the casing in position to depress the inner part of the lever 16 against the resistance of the spring 18. 75

Pivoted at 30 within the casing 14 is a bell crank lever 31 with one arm extending over the bolt 19 and the other arm connected 80 at 32 to a push rod extending through the front wall of the casing 14, and terminating in a push button 34. A spring 35 operates to maintain the bell crank lever yieldably against the bolt 19 and in the notch 22 to 85 hold the bolt yieldably in its outer position, or to lock the bolt from longitudinal movement when in its inner or withdrawn position.

A spring 36 operates to hold the bolt 19 90 yieldably in its outer or operative position.

Rigidly supported within the casing 14 is a rack bar 37, and pivoted at one end at 38 to the casing are rack bars 39, the latter being pivoted at their alternate ends as shown. 95 The swinging rack bars 39 are shorter than the rigid rack bars 37 so that the latter extends beyond the former at each end, as shown more particularly in Figure 3.

Mounted through the front wall of the 100 casing 14 is a short shaft 40 having a turning knob 41 at the outer end and a pointer or indicator 42 movable over a graduated dial 43 attached to the outer face of the casing.

At its inner end, within the casing 14, the

shaft 40 is coupled by a universal joint 43 to another shaft 44, the latter carrying a gear pinion 45 adapted to engage the stationary rack bar 37 and the swinging rack bars 39, as hereafter explained.

Initially the bolt 19 is disposed in its withdrawn position, leaving the lock lever 16 free to be moved on its pivot 15 against the resistance of the spring 18.

10 The door 10 is then closed which movement causes the hooked end of the lever 16 to enter the casing 12 and engage the stop 13, as shown in Figure 3, thus effectually locking the door to its jamb, as shown in 15 Figure 1.

The push rod 33-34 is then actuated to release the bolt 19 which is moved longitudinally to dispose its outer end beneath the inner end of the lever 16 and lock the latter 20 from disengagement from the stop 13.

The knob 41 is then rotated to dispose the pinion 45 in position upon the stationary rack 37.

The number of teeth on the rack bars will 25 be determined, and the graduations on the dial 43 will correspond with the teeth on the bars and may be varied to any required extent. For instance the number of teeth on the stationary rack bar will require the 30 knob 41 to be rotated a certain number of times to move the shaft 44 to the left until the pinion 45 passes beneath the first swinging rack bar 39 and permits it to drop by its free end in the path of the pinion and 35 by reversing the motion of the knob the pinion "rides" over the first swinging rack bar and when it reaches a certain predetermined position it elevates the second swinging rack bar and permits it to drop into 40 the path of the pinion. This second position of the pinion corresponds to one of the graduations on the dial, known to the operator, who when this position is noted, reverses the movement of the knob 41 and 45 causes the pinion to "ride" over the third swinging rack bar, and so on through the series until the pinion mounts the upper swinging rack bar when the continued rotation of the knob will cause the shaft 44 50 to engage the arm 26 and rotate the shaft 24 and gear 25 and move the bolt 19 longitudinally against the resistance of the spring 36 and release the lever 16 which may then be uncoupled from the stop 13 by actuating 55 the outer arm 28 and the inner arm 29, as before described.

By varying the lengths or the number of teeth in the rack bars 39 the numbers of revolutions of the knob 41 required to move 60 the pinion 45 into position on the upper rack bar 39 where its continued rotation will actuate the arm 26 to withdraw the bolt 19, may be correspondingly varied. Thus the 65 "set" of the lock may be varied to an almost unlimited extent, as will be obvious.

The improved device is simple in construction, can be manufactured of any required size, of any required proportions or of any required material, and will operate effectually for the purposes described.

70 The preferred embodiment of the invention is disclosed in the drawings and set forth in the specification, but it will be understood that modifications within the scope of the claimed invention may be made in 75 the construction without departing from the principle of the invention or sacrificing any of its advantages.

Having thus described the invention, what is claimed as new is:—

80 1. A combination lock including a movable bolt, means for actuating the bolt, a plurality of rack bars pivoted to swing at their alternate ends, and a shaft carrying a gear pinion consecutively engageable with said rack bars, said shaft operative to engage the bolt moving means when the pinion arrives at a predetermined position on the rack bars.

85 2. A combination lock including a movable bolt, means for actuating the bolt, a pivoted locking lever engageable by the bolt when in one position, a plurality of rack bars pivoted to swing at their alternate ends, and a shaft carrying a gear pinion consecutively engageable with said rack bars, said shaft operative to engage the bolt moving means to release the locking lever when the pinion arrives at a predetermined 90 position on the rack bars.

95 3. A combination lock including a movable bolt, means for actuating the bolt, a stationary rack bar, a plurality of rack bars coacting with the stationary rack bar and pivoted to swing at their alternate ends, and a shaft carrying a gear pinion consecutively engageable with said rack bars, said shaft operative to engage the bolt moving means when the pinion arrives at a predetermined position on the rack bars.

100 4. A combination lock including a movable bolt, means for actuating the bolt, a pivoted locking lever engageable by the bolt when in one position, a spring operating to hold the lever yieldable in one position, means for moving said locking lever into releasing position against the resistance of said spring, a plurality of rack bars pivoted to swing at their alternate ends, and a shaft carrying a gear pinion consecutively engageable with said rack bars, said shaft operative to engage the bolt moving means when the pinion arrives at a predetermined position on the rack bars.

110 5. A combination lock including a movable bolt having a gear rack, a gear engageable with said gear rack, a plurality of rack bars pivoted to swing at their alternate ends, and a shaft carrying a gear pinion consecutively engageable with said rack 115 bars.

120 5. A combination lock including a movable bolt having a gear rack, a gear engageable with said gear rack, a plurality of rack bars pivoted to swing at their alternate ends, and a shaft carrying a gear pinion consecutively engageable with said rack 125 bars.

bars, said shaft operative to engage the gear wheel and thereby actuate the bolt when the pinion arrives at a predetermined position on the rack bars.

5 6. A combination lock including a movable bolt having a gear rack, a shaft having a laterally directed arm, a gear on said shaft engaging said gear rack, a plurality of rack bars pivoted to swing at their alternate ends, a shaft carrying a gear pinion consecutively engageable with said rack bars, said shaft operative to engage the laterally directed arm and rotate the gear and thereby actuate the bolt when the pinion 10 arrives at a predetermined position on the rack bars.

7. In a device of the class described, co-acting casings adapted to be attached respectively to a door and its frame, a stop 20 member in one of said casings, a lock lever swingingly mounted in the other of said casings and having a terminal hook engageable with said stop member, a movable bolt in the casing which supports the lock lever 25 and operating when in one position to hold the lock lever in engagement with the stop

member, a plurality of rack bars pivoted to swing at their alternate ends, and a shaft carrying a gear pinion consecutively engageable with said rack bars, said shaft operative to engage the bolt moving means when the pinion arrives at a predetermined 30 position on the rack bars.

8. A combination lock including a casing, a bolt movable in said casing, means for 35 actuating the bolt, a plurality of rack bars pivoted to swing at their alternate ends within said casing, a shaft carrying a gear pinion consecutively engageable with said rack bars, said shaft operative to engage the 40 bolt moving means when the pinion arrives at a predetermined position on the rack bars, and a graduated dial upon said casing, and a pointer on said shaft coacting with the graduations on the dial to denote the 45 position of the pinion relative to the swinging rack bars.

In testimony whereof, we affix our signatures hereto.

CHARLES J. ANDERSON.
WILLIAM H. VAN DYKE.
